UNITED STATES PATENT OFFICE.

JOSEPH BULOVA, OF NEW YORK, N. Y.

JEWELRY.

SPECIFICATION forming part of Letters Patent No. 363,725, dated May 24, 1887.

Application filed April 9, 1887. Serial No. 234,286. (No model.)

To all whom it may concern:

Be it known that I, JOSEPH BULOVA, a citizen of the United States, residing at New York, county and State of New York, have invented 5 a new and useful Improvement in Jewelry, of which the following is a specification.

This invention relates to an improvement on Letters Patent No. 327,431, granted to me September 29, 1885, and which describes a 10 finger-ring the stone of which is held to the head by means of two pins entering grooves in the edges of the stone.

The present invention has for its object to permit the attachment of the stone to the ring 15 or other article of jewelry by means of but one elastic central tongue or rail, which enters a dovetail groove cut into the lower face of the stone.

The invention consists in the various features of improvement hereinafter more fully 20 pointed out.

In the accompanying drawings, Figure 1 represents a side view of a finger-ring provided with my improvement. Fig. 2 is a longitudinal central section of the same. Fig. 3 is a cross-section on the line $x-x$, Fig. 2. Fig. 4 is a vertical face view of the tongue e .

The letter a represents a finger-ring or other article of jewelry, having the flanges or sides

b , between which the stone c is set. This 30 stone is provided at its lower face with a dovetail central groove, c' , such groove receiving a dovetail tongue or rail, e , that extends also through holes or notches f in the flange b . To attach the stone to the ring, it is simply 35 necessary to push the rail through the holes or notches f and through the groove in the stone c , and owing to the dovetail shape of the parts the stone will be securely held in place.

The tongue e is made with a central slot, e' , 40 and is bulged outward slightly at the center of its long sides. Thus the tongue will have a springing or elastic action, and will tightly fit into its seat c' . Were it not for this construction, the tongue would be rigid, and it 45 would be very difficult to so thoroughly fit the tongue as to prevent rattling of the stone.

What I claim is—

The combination of an article of jewelry, a , having the sides b , with the stone c , having a 50 dovetail groove in its lower face, and with the elastic rail e , adapted to fit said groove, substantially as specified.

JOSEPH BULOVA.
